UNITED STATES PATENT OFFICE.

ISAAC H. ATHEY, OF CHICAGO, ILLINOIS, ASSIGNOR TO ATHEY TRUSS WHEEL CO., OF CHICAGO, ILLINOIS, A CORPORATION OF ILLINOIS.

SHOE FOR TRACKLAYING VEHICLES.

Application filed October 21, 1922. Serial No. 595,905.

To all whom it may concern:

Be it known that I, ISAAC H. ATHEY, a citizen of the United States, and resident of Chicago, in the county of Cook and State 5 of Illinois, have invented a certain new and useful Improvement in Shoes for Track-laying Vehicles, of which the following is a full, clear, concise, and exact description, reference being had to the accompanying 10 drawings, forming a part of this specification.

My invention relates to improvements in shoes for track-laying vehicles, and is particularly concerned with, though not limited 15 to, improvements in shoes for that type of vehicle employing a trussed chain or track.

The principal objects of my invention are to provide a shoe for the purpose described, in which the various parts thereof are so 20 arranged relatively to each other as to produce a construction of minimum weight and maximum strength.

A further object of my invention is to provide a shoe such as described which can 25 be readily manufactured by the casting process.

Other objects of my invention will appear as this description progresses, reference being had to the accompanying drawing, in which:

Figure 1 is a side elevation of a portion of a trussed track or chain formed of links embodying my invention;

Figure 2 is an end elevation of a link 35 embodying my invention, certain portions thereof being broken away;

Figure 3 is a transverse section taken on line 3—3 of Figure 2;

Figure 4 is a horizontal section taken on 40 line 4—4 of Figure 2;

Figure 5 is an enlarged detail view of the part shown in section in Figure 2; and

Figure 6 is a side elevation of one of the 45 closures for sealing the ends of the bores which receive the pintles that pivotally connect adjacent shoes.

Throughout the several views, similar reference characters will be used for referring to similar parts, and the sections are taken 50 looking in the direction of the small arrows.

Referring for the present to Figures 2, 3 and 4, my improved shoe comprises an integral casting having the inner plate 5 and the outer or tread plate 6 forming a tread member. Interconnecting the inner and tread

plates and projecting therefrom at one side of the shoe is a bearing lug 7. A pair of bearing lugs 8 interconnect and project from the inner and tread plates at the opposite side of the shoe, these lugs being arranged 60 in spaced relation for the purpose of receiving the bearing lug 7 of the next adjacent shoe and being pivotally connected thereto by means of a suitable hinge pin or pintle 9 (see Fig. 1). Openings 10, extending 65 through one side of the lugs 8, are provided for receiving pins 11 (see Fig. 2), which bear against the ends of the pintle 9 for holding the same in place.

From an inspection of Figures 2 and 5, it 70 will be noted that I make the pintles 9 somewhat shorter than the bearing bores in which they are located, and that the ends of the bearing bores are enlarged or counter-bored as shown at *a* in Figure 5. To prevent the 75 ingress of sand and dirt between the outer ends of the pintle and the bearings for it, I insert bottom first a cup-shaped end closure *b*, which has oppositely disposed notches *c* formed in the flange thereof. I then insert 80 a pin 11 through the opening 10 formed in one side of the bearing lug, this pin passing through the aligned notches *c* in the cup and into an opening *d* formed in, but not extending entirely through, the opposite side of the bearing lug. Originally the pin 11 is somewhat longer than the distance from the bottom of the opening *d* to the outside of the opposite side of the bearing lug. The projecting end of the pin is then given 85 one or more heavy blows which expand the ends of the pin in the openings. To still further insure against the loss of the pin 11, I insert a punch in the outer end of the bearing bore, place it against the pin and 90 give it a heavy blow, which causes the intermediate portions of the pin to be offset relatively to the ends thereof, as shown in Figure 5.

By the construction referred to above, I 100 not only provide means for preventing sand and dirt from working in between the walls of the bore and the pintle, but I also provide means for preventing the end of the pintle from wearing the pins 11.

The lugs 7 and 8 serve to hold the inner plate and tread plate in spaced relation and lie between the planes of these two plates, as clearly shown in Figure 3. The remaining margins or edges of the plates 5 and 6 110

are held in spaced relation by means of the end walls 12 and the side walls 13. The transversely extending fillets or webs 14 reinforce the central part of the tread plate 5. 6. A pair of truss arms 15 are secured,— that is, formed integrally with the inner plate 5—and span the connections between this inner plate and the bearing lug 7 so as to form reinforcements for these connections. For this purpose and also for the purpose of securing maximum strength with minimum weight, these truss arms are made L-shaped in cross section and one flange 15' thereof extends transversely of the shoe. A similar pair of truss arms 16 are connected with the opposite side of the inner plate 5 and are so arranged as to reinforce the connections or joints between the bearing lugs 8 and the inner plate 5. 20 The inner or free ends of the truss arms 15 and 16 converge toward each other so that each truss arm 15 merges at its inner or free end with the end of the adjacent truss arm 16. The inner merging ends of 25 the two sets of truss arms are each provided with a bearing 17 for receiving the pins 18 (see Fig. 1) of the truss chain 19. The outer ends of the merging truss arms are also connected by means of the brace 20, 30 which is formed integrally therewith.

The particular construction of the truss chain 19 forms no part of my present invention, but a full description thereof may be found in my United States Patent No. 35 1,458,962, granted June 19, 1923.

By reference to Figures 3 and 4, it will be noted that the central portion of the inner plate is cut away as shown at 21. This is done for the purpose of decreasing the 40 weight of the shoe and also to permit the ready removal of the cores from the hollow portions of the shoe after it has been cast.

Secured to the outer side of each of the truss arms 16 and the adjacent portion of 45 the inner plate 5 is a shoe aligning plate 22. The function of this plate is to provide means for automatically aligning the shoes with the inner side of the load supporting wheel 24. In the preferred embodiment of 50 my invention, one of these wheels will roll upon each end of the inner plate 5, as shown in Figure 2.

From the above description, it will be apparent that I have provided a shoe in which 55 the parts are so arranged with relation to each other as to provide a maximum amount of strength with minimum weight. It will also be noted that the parts are arranged so as to expedite the casting and machining 60 thereof.

While I have described the details of construction of the preferred embodiment of my invention, it is to be understood that my invention is not limited to these details, but 55 is capable of other adaptations and modi-

fications within the scope of the appended claims.

Having thus described my invention, what I claim is:

1. A vehicle track-side comprising an inner plate and a tread plate arranged in spaced relation, a bearing lug interconnecting and reenforcing the plates and serving as an element for the attachment of another shoe, and a truss arm projecting from the inner plate and bridging the connection between the inner plate and the bearing lug to reinforce and strengthen the same. 70 75

2. A unitary track-shoe comprising a tread member, a bearing lug projecting from the tread member to serve as an interconnecting element with another shoe, and a truss arm bridging the connection between the tread member and the bearing lug, the tread member, bearing lug and truss arm being integrally formed. 80 85

3. A unitary track-shoe comprising a tread member having projecting bearing lugs which serve in connecting the shoe with other shoes, a truss structure bridging and reenforcing the connections between the tread member and the bearing lugs and adapted to co-operate with the truss structures of adjacent shoes to hold the track rigid under load, and a shoe-aligning plate 90 95 bridged to the truss structure; the tread member, bearing lugs, truss structure and shoe-aligning plate being integrally formed.

4. A flexible track for a vehicle, comprising a plurality of shoes, the adjacent sides 100 of which are provided with overlapping bearing lugs, said lugs having aligned openings formed therethrough forming a bearing bore, a pintle in each bore, said pintle being shorter than said bore, and means for closing each end of said bore comprising a cup-shaped closure inserted bottom first in said end, the flanges of said cup having oppositely disposed notches cut therethrough and a pin extending through the one wall of 105 said bore and said notches for holding said cap in place, the central portion of said pin being offset from the end portions thereof. 110

5. A flexible track for a vehicle, comprising a plurality of shoes, the adjacent sides 115 of which are provided with overlapping bearing lugs, said lugs having aligned openings formed therethrough forming a bearing bore, a pintle in each bore, said pintle being shorter than said bore, and means for closing each end of said bore comprising a cup-shaped closure inserted bottom first in said end, and a pin extending through the one wall of said bore for holding said cap in place, the central portion of said pin being offset from the end portions thereof. 120 125

6. A flexible track for vehicles comprising a plurality of shoes the adjacent sides of which are provided with overlapping bearing lugs, each set of overlapping lugs 130

having aligned openings to form a bearing bore, a pintle located in the bore to hold the lugs together and being shorter than the bore, a cup-shaped closure inserted bottom first in the bore to close an end thereof, and a pin extending into one of the bearing lugs and bearing against the closure to hold the closure and pintle in place within the bore.

5. A flexible track for vehicles comprising a series of track shoes each of which has a transverse hole adjacent opposite sides, the holes of adjacent shoes aligning to form a bearing bore, a pintle in each bearing bore to hinge adjacent shoes together, each pintle being shorter than its bore, a flanged closure for an end of each bore, and a pin passing through a flange of each closure and into a shoe to hold the closure and pintle in place.

6. A flexible track for vehicles comprising a series of track shoes each of which has a transverse hole adjacent opposite sides, the holes of adjacent shoe aligning to form a bearing bore, a pintle for each bore to hinge adjacent shoes together, each pintle being shorter than its bore, a pin extending across

each bore to hold a pintle in place, and a closure insertable in each bore between a pintle and pin for closing the bore and protecting the pin from abrasion by the pintle.

7. A flexible track for vehicles comprising a series of track shoes each of which has a transverse hole adjacent opposite sides, the holes of adjacent shoes aligning to form a bearing bore, a pintle in each bearing bore to hinge adjacent shoes together, each pintle being shorter than its bore, a flanged closure for an end of each bore, and a pin passing through a flange of each closure and into a shoe to hold the closure and pintle in place.

8. A flexible track for vehicles comprising a series of track shoes each of which has a transverse hole adjacent opposite sides, the holes of adjacent shoe aligning to form a bearing bore, a pintle for each bore to hinge adjacent shoes together, each pintle being shorter than its bore, a pin extending across
